DESIGN FOR A COMBINATION BEARING SUPPORT, RETAINER, AND STOP ATTACHMENT FOR VENETIAN BLINDS

Edwin Anderson, Los Angeles, Calif., assignor to Anderson Die Casting and Engineering Corporation, Los Angeles, Calif., a corporation of California

Application May 11, 1937, Serial No. 69,300

Term of patent 14 years

To all whom it may concern:

Be it known that I, Edwin Anderson, a citizen of the United States, residing at Los Angeles, in the county of Los Angeles and State of California, have invented a new, original, and ornamental Design for a Combination Bearing Support, Retainer, and Stop Attachment for Venetian Blinds, of which the following is a specification, reference being had to the accompanying drawing, forming part thereof.

Figure 1 is a front elevational view of a combi-

nation bearing support, retainer, and stop attachment for Venetian blinds, showing my new design;

Figure 2 is a side view thereof;

Figure 3 is a view thereof seen from the opposite side.

I claim:

The ornamental design for a combination bearing support, retainer, and stop attachment for Venetian blinds, as shown.

EDWIN ANDERSON.
